UNITED STATES PATENT OFFICE.

JOHN W. DWIGGINS, OF FRANKTON, INDIANA, ASSIGNOR OF TWO-THIRDS
TO A. D. HURST AND WM. H. H. QUICK, OF SAME PLACE.

DESIGN FOR A FENCE-PANEL.

SPECIFICATION forming part of Design No. 22,358, dated April 18, 1893.

Application filed January 13, 1893. Serial No. 458,305. Term of patent 7 years.

To all whom it may concern:

Be it known that I, JOHN W. DWIGGINS, of Frankton, county of Madison, and State of Indiana, have invented a certain new and original Design for Fences; and I do hereby declare that the following is a full, clear, and exact description thereof, reference being had to the accompanying drawing, in which like figures refer to like parts.

- 10 The figure is an elevation of a panel of a fence showing my design.
1 are the posts.
2 is a rail connecting the two posts of the fence panel. There are four horizontal strands 15 of wire 4 extending between the fence posts. Entwined with these horizontal strands are vertical strands 5 extending from the bottom to the top of the fence and looped at the top at 6, and extending down again to the bottom, 20 so that one of such looped strands forms a kind of panel, and the wires of these panels adjoin each other successively from top to bottom. Within each of these panels is another strand of wire 7, which begins at the 25 bottom of the fence attached to one side of one of such panels, extending vertically to the first horizontal strand, then diagonally to the junction of the second horizontal strand to the other side of the panel, and then diagonally 30 in the opposite direction to the junction of the

third horizontal strand to the side of the panel, then extending up a short distance and looped to the other side of the panel, extending down to the third horizontal strand, then diagonally down to the junction of the second 35 horizontal strand to the other side of the panel, and then diagonally down therefrom to the junction of the lowest horizontal strand of the panel, and then vertically down to the end of the panel.

40 The essential features of my design consist in horizontal strands crossed by vertical panels consisting of strands looped at the top and extending vertically to the bottom of the design and inclosing another strand looped above 45 the second horizontal strand from the top of the design and extending downward within the outer strands of such panels and crossing from one side to the other of the same between each pair of horizontal strands like lattice work.

50 What I claim as my invention is—

The design for a panel of fence substantially as shown and described.

In witness whereof I have hereunto set my hand this 21st day of December, 1892.

JOHN W. DWIGGINS.
